UNITED STATES PATENT OFFICE

164,503

COMBINED GOLF CLUB AND GOLF BALL CARRIER

Allan Wesley Kerr, Westmount, Quebec, Canada

Application February 7, 1949, Serial No. 727
In Canada December 11, 1948

Term of patent 14 years

(Cl. D34—5)

To all whom it may concern:

Be it known that I, Allan Wesley Kerr, a subject of the King of Great Britain, residing at 335 Clarke Ave., in the city of Westmount, Province of Quebec, Dominion of Canada, have invented a new, original, and ornamental Design for a Combined Golf Club and Golf Ball Carrier, of which the following is a specification, reference being had to the accompanying drawing, forming part thereof.

In the drawing:

The dotted line showing of the golf balls is for illustrative purposes only.

I claim:

The ornamental design for a combined golf club and golf ball carrier, as shown and described.

ALLAN WESLEY KERR.
